UNITED STATES PATENT OFFICE.

FRANK H. G. MORSE, OF CAMBRIDGE, MASSACHUSETTS.

BOX.

No. 856,281.

Specification of Letters Patent.

Patented June 11, 1907.

Application filed January 26, 1907. Serial No. 354,193.

To all whom it may concern:

Be it known that I, FRANK H. G. MORSE, a citizen of the United States, and a resident of the city of Cambridge, county of Middlesex, State of Massachusetts, have invented new and useful Improvements in Boxes, of which the following is a specification.

My invention relates to boxes and it has particular reference to boxes which are 10 tightly closed to prevent the contents thereof from escaping by reason of volatilization or evaporation. It has moreover reference to boxes which are to be tightly sealed and to means for easily opening such boxes.

When boxes are to contain a volatile substance it is absolutely necessary that there be a very tight closure between the cover and the body of the box. It is usual to make such a box so that the cover partially telescopes over the box, or vice versa, so that there will be a considerable surface of contact between the body and the cover of the box. The surfaces of the two being tightly compressed together it is exceedingly difficult to 25 separate them by reason of friction and by reason of sticking of the surfaces which may be due to enamel or other finishing material used for covering one of the surfaces.

In my invention I provide a means where- 30 by the cover may be easily wedged or pried from the body of the box without in any way injuring or altering the contact surfaces or de- stroying the shape of the box and which may be as tightly closed after opening the same as 35 before opening.

The invention consists in providing a cover having a surface located in proximity to a surface located on the body of the box, the said surfaces being at an angle to each other.

40 The invention also consists in providing a means for a cover and a means on the body of the box which enables one to wedge the cover from the box or to pry the cover from the box.

45 The invention also consists in forming a box having a beading provided with an inclined surface at the top and a semi-circular surface at the bottom to give the said beading structural strength, and to enable the cover 50 to be pried off.

The invention consists in other features described in the following description, shown in the drawing and claimed in the claims.

55 Referring to the drawings, Figure 1 illustrates a side view of the box embodying my invention, a part of it being shown in section.

Fig. 2 illustrates a side view of a portion of the box showing the position of the means for wedging the cover from the box. Fig. 3 also illustrates a side view of a portion of the box 60 showing the operation in prying the cover from the box.

Having thus described my invention in general, I will describe its details by using reference numbers which in each of the figures refer to the same parts.

1 indicates the cover of the box. The cover of the box is provided with a flange 2 which extends downward from the top. The flange 2 is provided with a contact surface 3 which 70 presses tightly against the contact surface 4 located near and along the upper edge of the box. The cover 1 is provided with a right angular flange 5 which is located at the lower edge of the flange 2. This flange 5 extends 75 all around the box and is located just below the contact surface 3. The flange 5 greatly strengthens the cover and prevents bending of the flange and thus keeps it in close contact with the body of the box.

80 6 is the body of the box. It is provided with a bead 7. The lower half 8 of the bead 7 is circular in cross-section forming an angle substantially of ninety degrees. The upper part 9 of the beading 7 is inclined and extends 85 upward to the contact surface 4 and in proximity to the right-angular flange 5 when the cover is placed on the box. This forms a V-shaped space between the flange 5 of the cover and the inclined or conical surface of 90 the beading 9 located on the body of the box.

95 The beading and the right-angular flange may be used to open the box. The right angular flange gives surface to operate on while the beading is of such a shape that it will permit the cover to be removed by simply forcing an instrument diametrically into the V-shaped space and which is structurally formed so that the cover may be pried off without bending or injuring the beading 100 when used as a fulcrum.

105 In Fig. 2 I have illustrated the method of removing the cover from the box when it is wedged off. Any instrument having a dull point or edge or a square end and yet which is not too large to fit in between the edge of the flange 5 and the lower edge of the surface 9 of the beading may be used. I have illustrated a device 10 having a square end. The back of a knife or other device may be used. The device 110 10 is placed between the two surfaces and is then pushed inward between the flange 5 and

the inclined surface 9 and the cover is pushed upward as the device 10 moves along the inclined plane 9. The surface 8 is of such a shape that it greatly strengthens the beading 5 and the surface 9 so that if necessary a considerable force may be applied to the device 10 while removing the cover. The surface 9 being inclined with respect to the lower surface of the flange 5 the amount of pressure 10 exerted upward on the cover is multiplied accordingly.

In Fig. 3 is shown the method of removing the cover by prying it off. The tool is inserted between the flange 5 and the inclined 15 surface of the beading and the device is pressed downward using the lower edge of the inclined surface where it meets with and is strengthened by the circular surface of the beading as a fulcrum.

20 The invention may be modified by those skilled in the art without departing from the spirit thereof. Flanges of different shapes and forms and beadings of different shapes and forms can be used to permit opening 25 without departing from the essence of the invention. The beading may be placed on the cover of the box and the flange on the body of the box or the flange may be inclined and an inclined or horizontal surface located in 30 proximity thereto may be used on the body of the box without avoiding my invention.

What I claim as new and desire to secure by Letters Patent is as follows:

1. In a sheet metal stamped box the combination of a cover and the body of the box, 35 the cover having a flange consisting of two portions, one of said portions adapted to fit tightly around the outside of the body of the box and the other portion of the said flange

extending outward and at right angles to the 40 first mentioned portion, the body of the box having an enlarged portion, the said enlarged portion having an inclined surface, the upper edge of the said inclined surface adapted to make contact with the first mentioned portions of the said flange and to limit the position of the cover on the box, the said enlarged portion also having a circular cross-section of ninety degrees whereby the lower edge of the said inclined portion is strengthened. 45 50

2. In a box the combination of a cover and the body of the box, the cover having a flange consisting of two portions, one of said portions adapted to tightly fit around the outside of the body of the box and the other portion of the said flange extending outward and at right angles to the first mentioned portion, 55 the body of the box having an enlarged portion, the said enlarged portion having a conical surface extending from the outer edge of the said enlarged portion inward and upward to the body portion of the box and a rounded surface having a cross-section of substantially 90 degrees extending from the lower 60 edge of the said conical surface to the body portion, the upper edge of the said conical surface adapted to limit the position of the cover on the said box, the said conical surface adapted to form a V shaped space with 65 the right angular portion of the said flange. 70

In testimony whereof, I have signed my name to this specification, in the presence of two subscribing witnesses.

FRANK H. G. MORSE.
